UNITED STATES PATENT OFFICE.

KASPER SCHMITT, OF DEWAR, IOWA.

HEATER.

SPECIFICATION forming part of Letters Patent No. 442,141, dated December 9, 1890.

Application filed May 28, 1890. Serial No. 353,430. (No model.)

To all whom it may concern.

Be it known that I, KASPER SCHMITT, a citizen of the United States, residing at Dewar, in the county of Black Hawk and State of Iowa, have invented certain new and useful Improvements in Heaters, of which the following is a full and clear description, reference being had to the accompanying drawings, forming a part of this specification, in which—

Figure 1 represents a vertical sectional view of my heater, showing the several pipes in elevation. Fig. 2 is a detail of the water-pipes which form the inclosing fire-chamber, taken on the line $z z$ of Fig. 1 and looking toward the front. Fig. 3 is a cross-sectional view of the fire-chamber. Fig. 4 is a sectional view of a cooking-vessel to be referred to.

My invention relates to certain new and useful improvements in devices for heating water for domestic or stock purposes; and my invention consists in the constructions, combinations, and arrangements of parts, which I shall hereinafter fully describe and claim.

To enable others skilled in the art to which my invention appertains to make and use the same, I will now describe its construction and indicate the manner in which the same is carried out.

Referring to the drawings, A represents a casing of any well-known description, having a flue a for the escape of the products of combustion. A ledge or flange b surrounding an opening in the top of the casing furnishes a means for supporting a vessel B, which is let into said opening, and by preference has a curved bottom, above which, supported upon a ledge b' , is a false slatted bottom b'' , which may be used when desired.

Secured to or upon any well-known support, and preferably at a point above the casing A, is a vessel or tank C, adapted to contain water, and from said tank leads a pipe c , which extends downward to the base of the casing and enters the bottom thereof and extends upward a short distance, and is coupled to one of the pipes d in the horizontal lower coil D. This coil consists of the pipes d and d' , which connect near the central portion of the coil, and are then coiled right and left toward the sides of the casing, after which the pipes d and d' are coiled vertically along said sides for a suitable distance, and then are turned

inward and coiled to form a horizontal coil D' similar to the lower coil D, the two pipes d and d' of said upper coil being united and connected with a pipe e , which extends upwardly in the casing to a point near the top, and thence extends through the front of said casing and is coupled to a vertical pipe f , whose lower end is connected with a branch pipe g from the vertical pipe c , which leads from the water-tank, the said branch pipe having a controlling valve or cock h , and the pipe having a valve or cock k , which regulates the amount of water flowing to the coils.

The upper end of the vertical pipe f is coupled to a horizontal pipe l and is provided at its top with any well-known form of safety-valve f' , and this horizontal pipe l has one of its ends passing into the vessel or receptacle B, while the other end leads to and enters a cask, barrel, or vessel E, which contains feed for cattle or for other purposes.

The horizontal pipe l has valves m and m' , which may be operated to permit the flow of water or steam to the vessel B or to the vessel E.

In Fig. 4 I illustrate a supplemental vessel F, which is somewhat smaller than the vessel B, and is designed to be supported in said latter vessel, so that it is wholly or partially submerged, said vessel F having a removable platform G supported within it upon the ledge n and adapted to support such articles of food as may be placed thereon and cooked for table use.

From this description it will be seen that the coils D and D' with their vertical side members constitute a four-sided receptacle which forms a chamber for the fire, the fuel for which is placed upon the lower coil D through the door H in the casing, which may be of iron or masonry or may represent any well-known form of stove-casing. The regulating-valve k being opened and the valves h and m being closed, the water from the tank C flows through the vertical pipe c into the coils surrounding the fire, where it is heated, and thence flows through the pipes f and l into the vessel B and is discharged onto the clothes or other articles placed therein. If clothes are to be washed, they will be placed upon the slatted platform b'' to prevent their being burned by contact with the metal bottom of

the vessel. This arrangement enables me to supply hot water whenever needed for washing clothes or for cooking articles for table use, in which latter case the supplemental vessel is placed within the vessel B, as previously described.

If it be desired to cook the feed within the barrel or vessel E, I close the valve m' in the horizontal pipe l and open valve m , when the heated water and steam flow through the pipe f into the barrel. When it is desired to draw hot water for domestic purposes, the valves m and m' are closed and the valve in the branch pipe g opened, when the water may be drawn directly from the coils. The pipes of the lower coil may have one or more of their members provided with a draw-off cock I to withdraw the water in the coils and their pipes, and thereby prevent damage by freezing when the heater is not in use.

Having thus described my invention, what I claim as new, and desire to secure by Letters Patent, is—

1. The combination, with the casing and the water-tank, of the upper and lower coils consisting of the pipes d and d' , coupled together and coiled horizontally and vertically to form a four-sided fire-chamber, a pipe lead-

ing from the water-tank and connected centrally with the lower horizontal coil, a discharge-pipe leading from the upper horizontal coil, and a vessel supported in the open top of the casing, into which said discharge-pipe empties, said vessel having a slatted platform or false bottom, substantially as herein described. 30 35

2. The combination of the casing, the water-tank, the pipe c , leading therefrom to the lower coil, the pipes d and d' , forming horizontal and vertical coils and constituting a fire-chamber, a discharge-pipe from the upper coil, the horizontal pipe l , having the valves m and m' , and the vertical pipe which connects the discharge-pipe with the horizontal pipe, said vertical pipe having a safety-valve 40 at its upper end and the horizontal pipe having its opposite ends adapted to enter independent vessels, substantially as herein described. 45

In testimony whereof I have hereunto set my hand this 12th day of May, 1890.

KASPER SCHMITT.
